UNITED STATES PATENT OFFICE.

PAUL J. MILLER, OF BIRMINGHAM, ALABAMA.

COMPOUND PISTON FOR INTERNAL-COMBUSTION ENGINES.

Application filed July 15, 1921. Serial No. 485,055.

To all whom it may concern:

Be it known that I, PAUL J. MILLER, a citizen of the United States of America, residing at Birmingham, in the county of Jefferson and State of Alabama, have invented certain new and useful Improvements in Compound Pistons for Internal-Combustion Engines, of which the following is a specification.

10 My invention relates to a compound piston for internal combustion engines, the elements of the piston in their relative movements being controlled by air cushions which are automatically obtained and which 15 are subject to regulation in order to control the relative axial play between the elements of the piston.

It is characteristic of my invention that the inner piston shall carry the wrist pin 20 and that the outer piston shall be free to rotate about and to move axially of the inner piston.

One advantage of this construction is derived from the freedom of the outer piston 25 to turn about the inner piston and thus prevent uneven wear of, and a tendency to score, the cylinder walls.

My invention contemplates controlling the relative axial movement between the pistons by air cushions which are automatically produced and maintained and one at 30 least of which is controllable so as to limit the free play between the pistons. The importance of the axial play and of the cushioning control thereof are manifold. It will gradually relieve excessive jars and strains delivered to the crank shaft from explosions occurring on or near dead center positions of the pistons; the air cushions 35 will serve to prevent actual contact between the pistons and thus relieve the crank shaft of mechanical jars; the excessive initial thrust imparted by the explosion to the outer piston while near dead center position 40 will be in part absorbed by an air cushion and later applied, at a more effective leverage angle, to the crank; the inner piston having a limited play in both directions 45 from dead center position before moving the outer piston will cause a reduction in the dead center load on the cranks and will 50 reduce the vibration and cause the engine to run more smoothly; and, finally, as the outer piston will ride higher on its air cushion 55 during its scavenging stroke than on its com-

pression stroke it will more effectively scavenge the cylinder.

These and other advantages of my invention will be better understood by reference to the illustrative embodiment of my invention which is shown in detail in the accompanying drawings, in which:

Fig. 1 is a sectional view showing the pistons of a compound piston moving downwardly under the initial power stroke just 65 after the upper air cushion has absorbed the initial thrust.

Fig. 2 shows the compound piston in partial cross section moving upwardly on a scavenging stroke.

Fig. 3 is a detail view of part of the outer piston illustrating the screw ring more clearly.

Fig. 4 is a half sectional view of the inner piston.

Similar reference numerals refer to similar parts throughout the drawings.

1 designates a conventional explosive engine cylinder, the crank (not shown) of which is connected to a wrist pin 3 mounted 80 in the inside piston 4. This piston has the outer surface of its inner end reduced to form an air cushion chamber 5 between it and the inner wall of the outside piston 6. Through the inner reduced end of the piston 4 I provide a series of air relief ports 7 lying in a horizontal plane above a packing ring 8 and substantially spaced from the upper end of the chamber 5, above which is a packing ring 9 which engages the inner 90 cylindrical surface of the piston 6. The upper end of the inside piston 4 carries any desired number of additional packing rings 10 so as to effectively pack the joint between the inside and outside pistons so as to make 95 it as air tight as possible without interfering with free relative axial movements of the pistons. A sleeve 11 is screwed into the outer piston 6 above its reduced lower end 12, against which the packing ring 8 works. 100 The sleeve can be screwed into and out of the piston to regulate the depth of the annular air cushion chamber 5. The head of the piston 4 is provided with a taper valve seat formed in a bushing 13 which seat receives a taper valve 14 having a stem 15 which projects down into the chamber in the piston 4 and carries a seat 16 for the coil spring 17, which surrounds a guide 19 for the stem and at its upper end bears 110

against the perforated base of the bushing. The valve as thus disposed will seat against pressure between the heads of the two pistons and will open to relieve a predetermined vacuum between the piston heads. The outer piston carries the customary piston rings 18 and the two pistons may have any other standard shape.

The operation of my invention is as follows. Assuming the pistons, as shown in Fig. 1, to be about to commence the intake stroke, as the crank pulls the inner piston 4 down it moves the ports 7 into position to be closed by the sleeve 11 and when this occurs a body 15 of air will be trapped in the annular chamber 5 forming the lower air cushion which is the medium by which the inner piston draws down with it the outer piston. As the piston heads tend to move apart no appreciable 20 vacuum will occur to retard the relative downward movement of the inner piston because the valve 14 will open when necessary to prevent a vacuum. At the completion of the stroke and while holding its lower dead 25 center position the only weight and load bearing on the crank shaft will be that of the inner piston as the outer piston will be floating between the air cushion 5 and the air cushion between the piston heads. On the 30 compression stroke, the inner piston moves relatively to the outer piston a sufficient distance to compress the air cushion between the piston heads, causing the latter to lift the outer piston with it. The inner piston 35 4 thus gradually takes on the load of the outer piston and there is no jar or shock to the engine. At the completion of the compression stroke the air cushion between the piston heads will be compressed to an equal 40 extent with the charge in the cylinder. Upon firing, the explosion will take effect on the outer piston first further compressing the air cushion between the piston heads approximately equal the gas pressures above 45 the compound piston. This compression of the air cushion between pistons commences with the crank nearly on dead center and continues for a definite time interval during which the crank is moving farther from 50 its dead center position and thus the heaviest shock of the explosion is not immediately and directly transmitted to the crank shaft but the power thrust is imparted thereto in more or less gradual fashion and over a much greater and more efficient leverage sector of its angular travel than would be the case if a simple piston were used. Upon the completion of the power stroke the pistons 55 will be approximately in the positions shown in Fig. 2 and as they move for the scavenging stroke the piston 4 will compress air in the chamber above it so as to lift with it the outer piston, but there being no pressure for the outer piston to work against it will 60 ride much higher than during its compres-

sion stroke and to this extent will increase the displacement of the burnt gases and render a more efficient scavenging than would be possible with a solid piston. By screwing the sleeve in or out of the outer piston 6 70 the volume of the air trapped between the piston heads is controlled, because the sooner the ports 7 are closed the sooner the relative downward movement of piston 4 in the piston 5 is checked and hence the shallower the 75 air cushion chamber between the pistons. By this means I can regulate the compression of the charge by regulating the axial displacement between the pistons, it being understood that the inner piston has always 80 a fixed travel and that the extent of the compression is entirely controlled by the movement of the outer piston. It thus follows that the adjustable control of the relative axial movements between the pistons is 85 vital to an exact control of the compression.

It is to be understood that any valve mechanism may be employed to function in the manner described for the valve 14 to relieve a vacuum between the piston heads.

Having thus described my invention, what I claim as new and desire to secure by Letters Patent is:—

1. In an explosive engine, a compound piston comprising an outer piston, an inner piston telescoped in the outer piston, a crank shaft connection carried by the inner piston, and means utilizing air cushions to control the relative axial play between said pistons.

2. In an explosive engine, a cylinder and a compound piston working therein and comprising inner and outer pistons, a crank shaft connection to the inner piston, and adjustable means to trap air between the pistons on their down stroke.

3. A mechanism in accordance with claim 2, in which the inner piston carries an upwardly opening valve means to relieve a vacuum between the heads of the pistons on their down stroke.

4. In an explosive engine, a cylinder and a compound piston therein comprising an inner piston having a crank shaft connection, an outer piston both rotatable and axially movable on the inner piston, automatic means to relieve the vacuum between the piston heads of the compound piston, and means responsive to air pressure to cushion the relative axial movements between the pistons.

5. In an explosive engine, a cylinder and a compound piston therein comprising an inner piston having a crank shaft connection, an outer piston both rotatable and axially movable on the inner piston, and means to control the relative axial movements between the pistons by trapped bodies of air.

6. In an explosive engine, a compound piston comprising an outer piston, an inner

piston working with piston rings in the outer piston, valve means to relieve a vacuum between the piston heads, and co-acting portions at the inner ends of the pistons to 5 form an air trapping chamber, said chamber having relief ports adapted to be blanketed under predetermined conditions by the outer piston.

7. A piston in accordance with claim 6, in which the portion of the outer piston which 10 blankets said relief ports is in the form of an axially adjustable sleeve.

In testimony whereof I affix my signature.

PAUL J. MILLER.
